UNITED STATES PATENT OFFICE.

WILLIAM D. PALEN AND HERMANN BOGATY, OF PHILADELPHIA, PENNSYLVANIA,
ASSIGNORS TO THE PHILADELPHIA TEXTILE MACHINERY COMPANY, OF PHILA-
DELPHIA, PENNSYLVANIA, A CORPORATION OF PENNSYLVANIA.

DRIER.

1,345,225.

Specification of Letters Patent. Patented June 29, 1920.

Application filed October 3, 1919. Serial No. 328,234.

To all whom it may concern:

Be it known that we, WILLIAM D. PALEN and HERMANN BOGATY, citizens of the United States and Russia, respectively, (the said 5 BOGATY having declared his intentions of becoming a citizen of the United States,) and residents of Philadelphia, Pennsylvania, have invented certain Improvements in Driers, of which the following is a specification.

Our invention relates to certain improvements in driers of the type in which the material is carried through the chamber while air is circulated therein.

One object of our invention is to provide means for preheating the fresh air which enters the chamber.

A further object of the invention is to cool the dried material as it leaves the drier.

A still further object of the invention is to prevent the escape of heated air from the discharge end of the drying machine into the faces of the operators working at this end of the machine.

In the accompanying drawings:

Figure 1 is a side view, partly in section, of a drier illustrating our improvements;

Fig. 2 is a plan view;

Fig. 3 is an end view; and

Fig. 4 is a view showing one means of holding the baffles in position.

1 is the drying chamber which may be of any length desired. At one side of the drying chamber is the heating chamber 2, which 35 is connected to the drying chamber. 3, 3 are circulating fans mounted on shafts 4, driven in any suitable manner, for circulating air in the chambers. 5 is an endless conveyer of wire, or other suitable material, mounted on 40 chains adapted to sprocket wheels 6 and 7. The material is discharged onto this conveyer by any suitable feeding mechanism inclosed in a casing 8 at the feed end of the machine and the material is carried through

45 the machine in the direction of the arrow and is discharged at the opposite end of the machine. Air is usually admitted at the discharge end of the machine and through the space occupied by the endless conveyer, or 50 through separate openings in the casing. This introduction of fresh air into the heating chamber is apt to chill the air in circulation unnecessarily. Furthermore, no means

is provided for cooling the material before it leaves the machine.

By our invention, we provide a cooling compartment 9 at the discharge end of the machine and connect this compartment by a pipe 13 with the drying chamber so that cold air will be drawn through the material carried by the conveyer, which will cool the material and at the same time the air will be preheated before entering the main drying chamber.

In the present instance, the compartment 65 9 is formed by two walls 10 and 10^a, and in the inner wall 10^a is an opening closed by a hinged baffle 12 and in the wall 10 is an opening closed by a hinged baffle 11. The baffle 12 is adjusted so as to clear the material being dried, while the baffle 11 can be adjusted to allow more or less air to enter the compartment between the material and the baffles. An adjusting means, shown in Fig. 4, may be used consisting of an arm 15 70 on the baffle and a hinged bolt 16 arranged to pass through the arm and provided with a wing nut for adjustment.

By the above construction, cold air will be drawn through the material on the conveyer 80 and through the opening in the wall 10, also through the compartment 9 and pipe 13, which communicates at 14 with the drying chamber some distance in advance of the compartment 9.

The air, in traveling this distance, added to the hot air passing through the opening with the material, preheats the fresh air so that it enters the heating chamber comparatively warm. At the same time, the cool 90 air passing through the material, while the material is passing through the compartment 9, is gradually cooled. The passage of air into the drying chamber is due to the suction created by the circulating fan within 95 the drier.

While the invention is shown as applied to a special type of drier, it will be understood that it can be used with any type of drier in which the material is traversed 100 through the drying chamber.

We claim:

The combination in a drier, of a drying chamber; fans for circulating hot air in the chamber; an endless belt conveyer arranged 105 longitudinally in respect to the drier and

arranged to carry material through the drying chamber; a compartment at the delivery end of the apparatus through which passes the conveyer with the material; means for preventing air passing from the compartment directly to the heating chamber; and a pipe communicating with the upper portion of the compartment and with one side

of the heating chamber some distance back of the compartment so that the fresh air 10 drawn through the material on the conveyer will be preheated, while the material being discharged will be partially cooled.
